Letters Patent No. 86,715, dated February 9, 1869.

IMPROVEMENT IN STAIR-RODS.

The Schedule referred to in these Letters Patent and making part of the same.

To all whom it may concern:

Be it known that I, H. UHRY, of the city of New York, in the county of New York, and State of New York, have invented certain Improvements in Stair-Rods, and in the manner of fastening the same to the stairs; and I do hereby declare that the following is a full and exact description thereof, which will enable others skilled in the art to make and use my said invention, reference being had to the accompanying drawings, forming part of this specification, and marked D at upper right-hand corner, to distinguish said drawings from others for similar invention, already filed for examination in the United States Patent Office by myself.

This invention relates to the class of stair-rods which are made of wood.

It is designed, more especially, to obtain a secured fastening, entirely concealed from view, leaving to the rod, when fastened in its place, the appearance of being held there by two large-headed nails, in old style, avoiding the exhibition of any metallic fastenings.

The invention consists of the combination of the wooden rod with a rotary hollow-bead catch, or bolt, and a T-headed, triangular-headed, or L-headed screw, or nail, more fully described below, by means of which the said rod is fastened to the stairs; and

It furthermore consists in making the end of the rotary bolt pointed, to serve as marker, or gauge, for indicating the place on the stairs where the screws or nails are to be driven.

In my drawings—

Figure 1 represents a top view of one of my improved stair-rods, when turned back forenoon, and used as a gauge for marking the place of the screws on the stair-case M;

Figure 2 is a front view of my improved stair-rod, as seen when in place;

Figure 3 is a front view (full size) of a piece of the same, showing the fastening;

Figure 4 is a sectional view of the same through x-x, to show details;

Figure 5 is a view of the rotary bolt, or catch, as seen from the back of the rod; and

Figures 6 and 7 are modifications of the shape of the catch-plate and hook, for the sake of illustrating the same.

A is the wooden stair-rod, which may be made of any desired wood and shape for ornamentation, but which has, at the points where it is intended to be fastened to the stairs, holes, C C, and cavities, D D, made

by boring from the back of the rod, with a bit of proper size to form the cavity D to a proper depth, then, with a smaller bit, finishing the work, by making the hole C entirely through the thickness of the said stair-rod.

M represents the riser of the stairs, to which the rod is to be applied.

E is a rotary catch, or bolt, having a hollow head, made to fit in the circular cavity D, where it may be turned by applying the fingers to the bolt-nut G, which is fastened to the bolt E by the pin g.

The hollow head of the bolt E is covered with a sheet of metal, or catch-plate, a, properly fastened to the said head, and having a perforation made therein of an oblong shape, to receive the head of the screw or nail T.

T is a screw or nail, having its head of proper shape to correspond with the catch-plate a, opening, so that when the head of said screw or nail is passed through the same, and turned a sixth or a quarter of a turn on its axis, it will be fastened or locked in the hollow head of the bolt E. (In place of the screw T, I sometimes use a screw-eye.)

The piece E is introduced in the cavity D and C of the rod A, and fastened thereto by the washer G, being securely fixed to the piece E by the pin g, but the piece E has a free rotary motion on its own axis, in the said cavity D and C of the rod A.

The end, c, of the bolt E, is made pointed, so as to serve as a marker or space-gauge, to indicate (by being turned and pressed against the riser, as seen in fig. 1.) the place where the screws T T are to be driven.

To put my improved rod in place, after having marked the places, as above described, the screws T are driven in, and the rod being turned the other way, and held by the nuts G G, the rotary bolts E E are turned until the holes in the plates a a enter or slip over the heads of the screws T T, when, by a slight turning of the bolts E E, the rod is effectually fastened.

Claim.

The combination of the wooden stair-rod A with the rotary bolt E and the screw or nail T, arranged substantially as, and operating in the manner herein set forth.

H. UHRY. [L. S.]
